UNITED STATES PATENT OFFICE.

JOHN E. HOBBS, OF NORTH BERWICK, MAINE.

DOUBLE-ENDER SLEIGH-RUNNER.

SPECIFICATION forming part of Letters Patent No. 716,543, dated December 23, 1902.

Application filed June 21, 1901. Serial No. 65,497. (No model.)

To all whom it may concern:

Be it known that I, JOHN E. HOBBS, of North Berwick, in the State of Maine, have invented certain new and useful Improvements in 5 Double-Ende Sleigh-Runners, whereof the following is a specification, reference being had to the accompanying drawings.

My present improvements are particularly applicable to runners arranged to be detachably secured to the body of a sleigh, pung, or wheel-vehicle.

As hereinafter described, my invention comprises a unitary framework independent of the vehicle-body to which it may be attached 15 and consisting of a pair of counterpart runners having upwardly-curved ends connected by cross-bars rigidly braced to the respective runners.

In the accompanying drawings, Figure 1 is 20 a side view of a vehicle-body provided with a runner-framework conveniently embodying my improvements. Fig. 2 is a plan view of the sleigh-runner shown in Fig. 1. Fig. 3 is a rear elevation of the runner shown in Figs. 25 1 and 2. Fig. 4 is a side view showing in detail the peculiar construction of the runner side springs.

In said figures, A A are counterpart runners, which are connected at their front extremities by the cross-bar B and at their rear extremities by the cross-bar C. Each of said runners A comprises a wooden base-bar A', whose opposite ends a' are upwardly curved, as best shown in Fig. 1. Each of said base-bars A' is provided with a shoe A², of iron or steel, the extremities a² of which project beyond the curved ends a' of the base-bar and are respectively secured to the cross-bars B and C. Said cross-bars B and C are rigidly 30 secured to the base-bars A' by the trusses D, which are fixed at their crowns d to said cross-bars and provided with downwardly-divergent limbs d', fixed upon said base-bars. Each of said trusses D is braced by standards 35 D², the feet d² of which are fixed upon the respective base-bars A' intermediate of the limbs d' of the trusses. Said standards are secured to the limbs d' of the trusses at d³ intermediate of their height and extend laterally beneath the respective cross-bars B C, to which they are secured at d⁴. The proximal limbs d' of the trusses D upon the respect-

ive base-bars A' are connected by respective tie-bars E, which are secured to said limbs d' at d⁵, and said tie-bars E are connected with the base-bars intermediate of their length by means of the brackets e. The springs F, which connect the cross-bars parallel with the base-bars A', preferably comprise several leaves arched, as shown in Fig. 1, the respective leaves f of said springs F being extended beneath the respective cross-bars B C and upturned and recurved, so as to overhang said cross-bars. The overhanging ends of said springs F are mounted upon bearing-plates 60 b c upon the respective cross-bars B C, to which they are secured by the clip-bolts b' c', which preferably extend across the ends of the springs diagonally, as best shown in Fig. 2, so as to distribute the strain upon each 65 spring. The downwardly-turned ends f² of said springs F engage the inner edges of said cross-bars B C, as best shown in Fig. 4, and prevent longitudinal displacement of the springs. The cross-bar C terminates laterally at the outer faces of the opposed runners A; but the ends of the front cross-bar B project laterally beyond the runners A and are provided with couplings B' to engage the thills H, so that said bar B constitutes the 70 draft-bar of the unitary structure above described, which is so constructed and arranged as to be self-supporting independently of any vehicle-body. However, any preferred form of vehicle-body I may be conveniently mounted upon the yokes G, which are secured upon the springs F by the clip-bolts g, as indicated in Fig. 1, such body being secured to the yokes by any convenient means, such as 75 screws or bolts.

The structure above described is so arranged that the weight of the body I and its contents is distributed by the springs F to the cross-bars B and C in such manner as to tend to separate said cross-bars in the direction of the length of the runners, and said runners are braced against the strain thus produced by the arrangement of the trusses D, with the downwardly-divergent limbs fixed upon the base-bars A'. The tie-bars E also 80 serve to brace the trusses D against displacement in the direction of the strain placed upon them by said springs and tend to stiffen the base-bars A'.

It is to be noted that the construction and arrangement of the parts above described are such as to secure the maximum strength of the runners without interference with the light and graceful appearance of the latter. Moreover, although the base-bars A', braced and connected as above described, form a very rigid and substantial base for a vehicle the superimposed springs and parts connected therewith are so arranged as to afford the maximum resiliency of connection between the vehicle-body and the base-bars, thus insuring the comfort of the occupant of the vehicle. The turning and backing of the vehicle are of course facilitated by the provision of the upwardly-curved ends at the rear of the runners, which are thus rendered capable of riding over obstructions in the road against which ordinary runners would abut. Said upwardly-curved rear ends are also of advantage in that they enable the runners to pass gradually down and up cradle-holes in the road without the jarring incident to the employment of ordinary runners which terminate abruptly.

I do not desire to limit myself to the precise details of construction and arrangement hereinbefore described, as it is obvious that various modifications may be made therein without departing from the essential features of my invention.

I claim—

1. In a sleigh-runner, the combination with a wooden base-bar having upwardly-curved ends; of a metal shoe fixed to said bar and projecting beyond the ends thereof; two trusses comprising downwardly-divergent limbs fixed to said base-bar; and means respectively connecting the projecting ends of said shoe with the respective crowns of said trusses, substantially as set forth.

2. In a sleigh-runner, the combination with a base-bar having upwardly-curved ends; of two trusses having downwardly-divergent limbs fixed to said base-bar and respectively connected at their crowns with the respective curved ends of said bar; a tie-bar connecting the proximal limbs of said trusses; and a bracket connecting said base-bar and tie-bar, intermediate of the length of the latter, substantially as set forth.

3. In a sleigh-runner, the combination with two base-bars having counterpart upwardly-curved ends; of a cross-bar transversely connecting the front ends of the respective base-bars; a cross-bar transversely connecting the rear ends of the respective base-bars; and a spring extending parallel with said base-bars and fixed at its opposite extremities to the respective cross-bars, substantially as set forth.

4. In a sleigh-runner, the combination with two base-bars having counterpart upwardly-curved ends; of a cross-bar transversely connecting the front ends of the respective base-bars; a cross-bar transversely connecting the rear ends of the respective base-bars; two

springs extending parallel with said base-bars and fixed at their opposite extremities to the respective cross-bars; and yokes fixed to the respective springs and arranged to attach the runner to a vehicle-body, substantially as set forth.

5. In a sleigh-runner, the combination with a base-bar having upwardly-curved ends; of a shoe for said base-bar projecting beyond the curved ends thereof; cross-bars respectively fixed to the opposite projecting ends of said shoe; and two trusses comprising downwardly-divergent limbs fixed to said base-bar, and respectively connected at their crowns with the respective cross-bars, substantially as set forth.

6. In a sleigh-runner, the combination with a base-bar having upwardly-curved ends; of a shoe for said base-bar projecting beyond the curved ends thereof; cross-bars respectively fixed to the opposite projecting ends of said shoe; two trusses comprising downwardly-divergent limbs fixed to said base-bar and respectively connected at their crowns with the respective cross-bars; and tie-bars respectively connecting the proximal limbs of said trusses, intermediate of the height thereof, substantially as set forth.

7. In a sleigh-runner, the combination with a base-bar having upwardly-curved ends; of a shoe for said base-bar projecting beyond the curved ends thereof; cross-bars respectively fixed to the opposite projecting ends of said shoe; two trusses comprising downwardly-divergent limbs fixed to said base-bar and respectively connected at their crowns with the respective cross-bars; and standards fixed to said base-bar and to the limbs of the respective trusses, extending laterally beneath the respective cross-bars and respectively fixed thereto, substantially as set forth.

8. In a sleigh-runner, the combination with a base-bar having upwardly-curved ends; of a shoe for said base-bar projecting beyond the curved ends thereof; cross-bars respectively fixed to the opposite projecting ends of said shoe; two trusses respectively connected at their crowns with the respective cross-bars and having downwardly-divergent limbs fixed to said base-bar; and a spring extending parallel with said base-bar and fixed at its opposite extremities to the respective cross-bars, substantially as set forth.

9. In a sleigh-runner, the combination with a pair of wooden base-bars having counterpart upwardly-curved ends; of metal shoes for said base-bars projecting beyond the ends thereof; cross-bars respectively connecting the front and rear extremities of the base-bars; two trusses upon each of said base-bars respectively connected at their crowns with said cross-bars; standards fixed to said base-bars intermediate of the limbs of the respective trusses, fixed to said limbs intermediate of their height, extending laterally beneath the respective cross-bars, and fixed to the latter; tie-bars respectively connecting the

proximal limbs of the trusses upon each of said base-bars; and brackets respectively connecting said base-bars with said tie-bars intermediate of the length thereof; two springs 5 extending parallel with said runners and respectively connecting the cross-bars thereof, the ends of said springs being recurved beneath said cross-bars and fastened to the top thereof; and yokes for the respective springs, 10 secured thereto in parallel position and arranged to attach the runner to a vehicle-body, substantially as set forth.

10. In a sleigh-runner, the combination with two counterpart base-bars having upwardly- 15 curved ends; of cross-bars transversely connecting said base-bars at the respective ends thereof; and springs extending parallel with said base-bars, and connected at their opposite extremities with the respective cross- 20 bars, substantially as set forth.

11. In a sleigh-runner, the combination with two base-bars having counterpart upwardly- curved ends; of a cross-bar transversely connecting the front ends of the respective base- 25 bars, and projecting laterally beyond the same; a cross-bar transversely connecting the rear ends of the respective base-bars; thill-couplings fixed upon the projecting ends of said front cross-bar; springs connecting said 30 front and rear cross-bars; and means upon

said springs arranged to attach the runner to a vehicle-body, substantially as set forth.

12. In a sleigh-runner, the combination with two base-bars; of two cross-bars respectively connecting the front and rear ends of said 35 base-bars; springs extending beneath said cross-bars and comprising upwardly-curved ends overhanging said cross-bars and terminating in hooks engaged therewith; and means to secure the hooked extremities of 40 said springs upon said cross-bars, substantially as set forth.

13. In a sleigh-runner, the combination with two base-bars; of trusses having downwardly-divergent limbs fixed to said base-bars; cross- 45 bars transversely connecting the trusses of the respective base-bars; and standards fixed upon said base-bars, secured to said trusses, and extending laterally inward beneath the respective cross-bars; and means fixing the 50 inner extremities of said standards to said cross-bars, substantially as set forth.

In testimony whereof I have hereunto signed my name, at North Berwick, Maine, this 14th day of June, 1901.

JOHN E. HOBBS.
